ANTON E. WICKLAND AND ARTHUR T. BRITTON, OF SAN JOSE, CALIFORNIA.

LATHE ATTACHMENT.

1,138,821.

Specification of Letters Patent.

Patented May 11, 1915.

Application filed May 18, 1914. Serial No. 839,266.

To all whom it may concern:

Be it known that we, ANTON E. WICKLAND, a subject of the King of Sweden, and ARTHUR T. BRITTON, a citizen of the United States, residing at San Jose, in the county of Santa Clara and State of California, have invented new and useful Improvements in Lathe Attachments, of which the following is a specification.

This invention relates to a boring and grinding attachment for engine lathes.

In the present advanced state of the gas engine industry it has become standard practice among builders of the better grades of gas engines and automobiles to finish their cylinders by grinding on specially constructed grinding machines.

The object of the present invention is to provide a simple and substantial grinding and boring attachment which may be applied to any ordinary hollow spindle engine lathe without impairing its usefulness for regular work, and which is so constructed and adjusted that it may be used for reboring and grinding gas engine cylinders, and the like, with just as great effect and accuracy as machines which are especially constructed for that purpose only.

Another object of the invention is to provide the attachment with a novel form of adjustment by which a greater or lesser cut may be taken when reboring or grinding.

Further objects will hereinafter appear.

The invention consists of the parts and the construction and combination of parts as hereinafter more fully described, having reference to the accompanying drawings, in which—

Figure 1 is a partial side elevation of an ordinary hollow spindle lathe, showing the application of the invention. Fig. 2 is a horizontal section on line X—X, of Fig. 1. Fig. 3 is a detail view of the attachable boring head. Fig. 4 is a cross section on line V—V, of Fig. 2, showing the universal joint connection.

Referring to the drawings, A indicates in general an ordinary hollow spindle engine lathe; 2 the V's and shears; 3 the carriage,

and 4 the ordinary angle plate to which the cylinder 5, or other work to be handled is secured. The hollow spindle upon the lathe, indicated at 6, is threaded internally, as at 7, at the outer end to permit the application of a bearing extension 8, upon which an auxiliary driving pulley 9 is journaled. The inner end of the spindle is provided with the usual threaded extension 10, upon which the chuck is mounted. A special form of chuck is, however, used in the present instance; that is, when the boring and grinding attachment is to be applied. The chuck consists of an internally threaded hollow sleeve 11, which is provided with a head 12 on its outer end. The front face of the chuck 13, is provided with a dove-tail extension 14, and the center portion of said extension is bored out as at 15 to receive a screw 16. The screw proper is provided with an annular groove 17 which engages with a projection 18 in the face of the chuck. This is provided for the purpose of holding the screw in a fixed position within the head of the chuck.

18 indicates a spindle extension, the inner end of which is provided with a dove-tail groove, which is adapted to be slipped over the dove-tail extension 14 upon the face of the chuck. The center portion of this groove is slightly convex, and threaded, as at 19, to permit engagement with screw 16. The turning of the screw 16 will thus adjust the position of the spindle extension radially with relation to the center of the chuck and hollow spindle. Suitably journaled in the spindle extension, but preferably in the anti-friction bearings, indicated at 20 and 21, is a shaft 22. The inner end of said shaft is provided with a universal joint connection 23, by which connection is made with a secondary shaft 24. The outer end of said shaft is also provided with a universal joint 25 which is connected with a cap 26, secured to the auxiliary pulley 9. Any suitable form of universal joint may be used at 23 and 25, but preferably the type shown; that is, the cap 26 is provided with a square or hexagonal recess into which a head of simi-

lar shape formed on the end of shaft 23 may be inserted; the head being slightly smaller in diameter gives sufficient play to permit of universal action. This forms a very simple 5 and practical universal connection, which may be quickly assembled or disconnected, as condition may require.

Suitably secured on the outer end of shaft 21 is a grinding wheel 27. This wheel may 10 be constructed of any abrasive material, and may be as large or small as conditions may require.

In operation, cylinder 5, or other work to be handled, is first secured to the angle plate 15 4, which is mounted upon carriage 3. Chuck 11 is then screwed on to the threaded nose 10 of the main hollow lathe spindle. Screw 15 is then turned until extension spindle 18 has been adjusted radially the desired distance; the grinding wheel 27 of suitable size 20 having first been applied. Power is then applied to one of the slow-speed pulleys, indicated at 28, which are secured upon the hollow spindle, and will then cause the spindle with connected chuck 11 and extension 25 spindle 18 to turn in unison with same. The radial adjustment of spindle 18 should be such that a slight eccentric movement of same is produced. Power is then applied to 30 the auxiliary pulley 9, which is designed to revolve at high speed; and this is transmitted through cap 10, universal joint 24, shaft 23 and universal joint 22, to shaft 21, upon which the grinding wheel is secured. 35 The grinding wheel is thus revolved independently of the spindle, and any desired speed may thus be transmitted to same through pulley 9. The rotary movement transmitted through pulley 28 and extension 40 spindle 18 causes it to travel in an eccentric path. Carriage 3, upon which cylinder 5, to be ground, is mounted is then slowly advanced with relation to the grinding wheel, and may be fed in this direction in the usual 45 manner by the screw feed of the lathe.

The abrasive wheel is generally of slightly smaller diameter than the interior of the cylinder, but the eccentric movement of same will cause it to travel around the interior of the cylinder and consequently engage with every portion of same.

The extension spindle 18, mounted and adjusted in the manner shown, may also be used to great advantage where it is necessary to take a slight cut out of the cylinder before regrinding same. The grinding wheel is in this instance removed and a cutter-head 30 of suitable construction is applied. The outer end of the spindle being threaded 55 as at 31 for this purpose. The cutting tool 32, mounted in the head may be fastened in any suitable manner, and the depth of the cut is adjusted by screw 15.

The attachment here shown is simple in construction, and may be applied to any ordinary hollow spindle engine lathe without impairing its usefulness in any manner. It eliminates the use of especially constructed grinding machines; and furthermore, combines two machines in one, as either one of two machining operations may be employed; viz: boring or grinding. It enhances the value and enlarges the scope of the engine lathe, since it provides means for doing work heretofore impossible to accomplish on a lathe.

The materials and finish of the several parts of the attachment may be such as the experience and judgment of the manufacturer may dictate.

We wish it understood that various changes in form, proportion and minor details of construction may be resorted to within the scope of the appended claims, and that we do not wish to limit ourselves 85 to the specific design and construction here shown.

The term "cutting tool" hereinafter used in the claims is to be understood as meaning any tool or implement which is suitable for 90 abrading or cutting purposes.

Having thus described our invention, what we claim and desire to secure by Letters Patent is:

1. In combination with the spindle of a lathe having an exteriorly threaded end, a chuck threaded over said spindle end and having a head which latter is provided with a diametrically extending dove-tail extension, said extension being provided with a screw-threaded recess and a projection which extends into the recess, a spindle extension having a dove-tail groove which receives said dove-tail extension and also having a screw-threaded recess which registers with the screw-threaded recess of the dove-tail extension, a screw engaged in said registering recesses and having an annular groove which receives said projection, a work engaging element borne by the spindle extension, means to drive said element, and means to drive the spindle.

2. In combination with the spindle of a lathe, a chuck secured to the front end of the spindle and having a dove-tail extension, a member having a dove-tail groove which slidably receives said dove-tail extension, a rotatable screw engaged with the member and with the extension to move the member laterally of the spindle, means to hold the screw against endwise movement, a work engaging element borne by the member, means to rotate said element, and means to drive the spindle.

3. In combination with the spindle of a lathe, a chuck secured to the front end of the

spindle and having a dove-tail extension, a member having a dove-tail groove which slidably receives said dove-tail extension, means for adjusting the member in said groove, a work engaging element borne by the member, means to drive said member, and means to drive the spindle.

In testimony whereof we have hereunto

set our hands in the presence of two subscribing witnesses.

ANTON E. WICKLAND.
ARTHUR T. BRITTON.
